UNITED STATES PATENT OFFICE.

BERTHOLD A. LANGE, OF ST. LOUIS, MISSOURI.

EGG CRATE.

Application filed March 5, 1924. Serial No. 696,991.

The transportation of eggs is one of the largest and most difficult phases of commerce. The value of the egg and its fragility combine to make any saving of breakage of extreme economic importance. Many kinds of egg-cases or fillers have been tried, but all possess some defect or another. The construction herein shown and described is one of the best for protecting the eggs from breakage, and the specific object of this invention is to provide an egg-case or filler which is less flimsy and to stiffen or stabilize the same.

In the accompanying drawings forming part of this specification, in which like numbers of reference denotes like parts wherever they occur.

Figure 1 is a perspective view of one form of this invention; and
20 Figure 2 is a perspective view of another form, and showing two of the fillers arranged in tiers.

Referring to both modifications as shown in Figures 1 and 2, the crate filler or egg-case is composed of a plurality of interlocking partitions 1 and 2 arranged at substantially a right angle to each other and fastened together by any suitable locking means at the points where they pass or join each other. This may be accomplished by slits 3 in partitions 1, allowing partitions 1 to fit down in notches 4 in partitions 2. Otherwise stated, the partitions 1 and 2 are each slit and turned in opposite directions, so that 35 each fits in the slit in the other.

Projections 5 prevent the transmission of shock or jar or slippage to the eggs inserted in the compartments 6, acting as a buffer and preventing telescoping. When the said 40 extensions or projections 5 are bent or broken, the breakage is greatly increased. This is especially apt to occur when the partitions become curved or flexed laterally under unequal stresses, so that one, or only 45 a few, of the extensions 5 must bear the full force incurred by impact with the sides of the outer box or container for holding the fillers.

To prevent or minimize this condition, 50 and, also, for the purpose of stiffening the structure generally, upper flanges 7 and lower flanges 8 are formed as integral extensions from any of the end ones of the partitions 1 and 2. A flange 7 overlies the 55 top edge of projections 5 along one side of the filler, and a flange 8 underlies the bot-

tom edge of other projections 5, along another side of the filler.

While a flange 7 stiffens the top side of the crate it is entirely inadequate for stiffening the same in a practical manner, because it does not impart the desired stability by itself. It leaves the crate in a distinctly collapsible condition, which is very detrimental in egg shipments. It is only by the introduction of the other flange 8 on the bottom side of the filler that the filler assumes the desired and necessary firmness and stiffness. Flanges 7 and 8 stiffen the filler from both sides, namely top and bottom, 70 respectively. With only flange 7, and under the vicissitudes of transportation, the eggs will be broken by the shifting in shape of the filler. With the addition of the flange 8, however, and the bearing down of weight 75 upon flange 8, considerable rigidity is imparted to the structure as a whole, with the result that it becomes practically immovable. The flanges 7 and 8, besides stiffening the structure against flexing, also protect the 80 projections 5.

A diaphragm 9 is commonly used between tiers of egg-crates, as shown in Figure 2.

Those upper and lower edges of the projections 5 covered by the flanges 7 and 8, 85 respectively, are preferably lower, as shown at 10 in Figure 2 (a part of flange 7 being broken away to show this feature), than the remaining horizontal edges of the partitions not covered by the flanges 7 and 8, so that 90 the outside faces of the flanges 7 and 8 lie in plane with the free or uncovered horizontal edges of the filler.

In the form depicted in Figure 1, the parallel end walls 1 have both upper flanges 95 7 and lower flanges 8; while in the form shown in Figure 2, an end wall 1 has only the upper flange 7, the lower flange 8 projecting from the bottom of end wall 2. Otherwise stated, all the flanges of Figure 1 extend in the same direction, while in Figure 2 the upper flange 7 is at right angles to the lower flange 8. The form of Figure 2, therefore, possesses the additional advantage of being stiffened in two directions. In 100 105 the form shown in Figure 2, instead of a single flange 7 and a single flange 8, a pair of flanges 7 on parallel end walls; and a pair of flanges 8 on parallel end walls 2 may be used.

Having thus described this invention, I hereby reserve the benefit of all changes in 110

form, arrangement, order, or use of parts, as it is evident that many minor changes may be made therein without departing from the spirit of this invention or the scope of the following claims.

I claim:

1. A cellular filler for egg-crates comprising a plurality of intersecting strips of material spaced from each other to provide a series of egg-cells, the ends of said strips at each side forming projections extending beyond the outer strip at that side, one set of oppositely directed projections being cut-away to define reduced terminal portions, and a pair of strips of material arranged on the opposite side of said filler and having their ends terminating flush with the projecting ends of the parallel intersecting strips, said pair of strips having integral top and bottom flanges throughout their entire length and extending outwardly and lying in the same plane with the top and bottom edges respectively of the intersecting strips that run parallel with said pair of strips, the reduced terminal portions of said intersecting strips being engaged between the said flanges and terminating flush with the outer ends thereof.

2. A cellular filler for egg-crates comprising two sets of intersecting strips of material right angularly disposed in respect to each other and spaced to present a series of egg-cells, the ends of said strips at each side forming projections extending beyond the outer strip at that side, one set of oppositely directed projections being cut-away to define reduced terminal portions, and a pair of strips of material arranged on the opposite side of said filler and having their ends terminating flush with the projecting ends of the parallel intersecting strips, said pair of strips having integral top and bottom flanges throughout their entire length and extending outwardly and lying in the same plane with the top and bottom edges respectively of the intersecting strips that run parallel with said pair of strips, the reduced terminal portion of said intersecting strips being engaged between the said flanges and terminating flush with the outer ends thereof.

In testimony whereof I hereunto affix my signature.

BERTHOLD A. LANGE
